DES. 1957

Charles J. Shepard, of Brooklyn, N.Y.

Letters Patent No 1957 Dated June 14th 1864.

Design for the Plates of a Cooking Range.

The schedule referred to in these Letters Patent and making part of the same.

Best known that I, Charles J. Shepard, of Brooklyn, in the County of Kings and State of New York, have invented, made, or produced a new and original design and ornamental finish for the plates of Cooking Range; and I do hereby declare, that the following description and annexed drawings fully set forth and illustrate the same.

In the drawing Fig. 1 is a front elevation of the front plates of a range, showing the configuration and the ornamentation of the same. The oven doors are raised or ovalled, and are

ornamented in the centre as represented. The panels at each outer end of front and between the doors are ornamented with upright and the upper section and base panels with horizontal turned ornaments as represented. The centre or fire doors are raised or ovalled with ornamental figures in the centre, and the ash pit front with the same turned ornamental figures as the front. In the centre of the ash pit front is a register flue door as represented.

The top section is a series of heating ovens the front of which are ornamented with the same style of turned ornaments, as the lower section, and it has a finial section on each corner, and a finial centre forming an ornamental finish.

Fig. 2 is an end elevation of the range. Fig. 3 is the top plate in two sections on each side of centre plate as represented.

Fig. 4 is a centre ornament or finial as represented.

Hearing thus set forth and shown the ornamental design, finish or configuration, of any range plate, what I desire to secure by Letters Patent is

2

DES. 1957

The ornamental design and configuration of the front plates, doors, and top plates of each top and bottom sections, as described and represented in the drawings.

In witness whereof, I have hereunto set my signature this 26th Twenty sixth day of March 1863.
